UNITED STATES PATENT OFFICE.

THEODORE A. KOCHS, OF CHICAGO, ILLINOIS.

DESIGN FOR A BOTTLE.

SPECIFICATION forming part of Design No. 36,455, dated July 21, 1903.

Application filed June 8, 1903. Serial No. 160,668. Term of patent 7 years.

To all whom it may concern:

Be it known that I, THEODORE A. KOCHS, a citizen of the United States, residing at Chicago, in the county of Cook and State of Illinois, have invented a new, original, and ornamental Design for Bottles, of which the following is a specification, reference being had to the accompanying drawings, forming part thereof.

Having shown my invention, what I claim as new, and desire to secure by Letters Patent, is—

The ornamental design for a bottle, herein shown.

THEODORE A. KOCHS.
